CANTILEVER KIT

Application filed November 3, 1927. Serial No. 230,721.

This invention relates to kits, and more particularly to sheet metal kits of the cantilever type.

An object of the invention is to provide a kit having a cover and trays disposable in superposed position in the kit when the cover is closed.

Another object of this invention is to provide a sheet metal kit carrying one or more trays, which kit, when open, is arranged to support said tray or trays in cantilever fashion.

A further object of my invention is to provide a sheet metal kit carrying a tray, said kit being arranged to move said tray into outwardly extending position upon the opening of the cover, and vice versa.

Another object of this invention is to provide a kit carrying one or more trays arranged to be supported in cantilever fashion, said kit having a box and cover each of uniform vertical dimension.

A further object of the invention is to provide a sheet metal kit of the cantilever type, said kit having a relatively low center of gravity when said kit is open and the trays carried thereby are in extended position.

Another object of the invention is to provide linkage of advantageous characteristics for a sheet metal kit of the cantilever type.

A further object of my invention is to provide a sheet metal kit of the cantilever type having economical and advantageous features of construction.

Another object of this invention is to provide for a kit of the cantilever type means whereby positive support may be provided for the tray or trays of said kit when the cover is open and said trays are being supported in cantilever fashion.

A further object of this invention is to provide a cantilever kit having a pair of superposable trays, the upper of said trays being movable independently of the lower tray to a predetermined position whereby access may be had to either of said trays.

Other objects of my invention will be apparent to those skilled in the art from the following description and annexed drawings.

My invention contemplates an improved sheet metal kit of the cantilever type, and in one embodiment contemplates an improved kit for carrying fishing tackle and the like. By my present invention I have provided a kit including a box and cover each of substantially uniform vertical dimension, whereby simplicity of construction and economy of manufacture may be obtained. The kit carries one or more trays which, when the kit is closed, are disposed in superposed position within the kit and spaced from the bottom of the box, whereby storage space may be had within the box below said trays. The trays are connected to each other and to the box and cover by links, whereby when the cover is opened the trays are moved to a position over the rear wall of the box, exposing the contents of the upper tray and of the box, the upper tray being independently moved to outwardly extended position to expose the contents of the lower tray. When the lower tray is in outwardly extended position both trays receive a positive support from the surface upon which the kit is supported through the cover and associated links. The lower tray is connected to the box by an advantageous curved link construction whereby the lower tray when in outwardly extended position assumes a position in a relatively low vertical plane adjacent the top rear edge of the box. In this manner the kit as a whole may have a relatively low center of gravity when the kit is open and the trays are in outwardly extending position.

One of the trays and the cover are connected by "extensible links", by which term I refer broadly to any link wherein the distance between the pivotal connections thereof varies during the operation thereof. I prefer to employ "compound links" for the connection between the trays and cover due to the smoothness of operation to be obtained thereby. By a "compound link" I refer to a link comprising a plurality of link elements.

In the drawings:

Figure 1 is a perspective view of a kit embodying my invention, the cover being open and both trays in extended position.

Fig. 2 is an end elevation of the kit shown in Fig. 1, showing the cover open, the lower tray in outwardly extending position, and the upper tray still in superposed position upon the lower tray.

Fig. 3 is a fragmentary front elevation of the kit, portions of the front walls of the cover and box being broken away to show the interior of the kit.

Fig. 4 is a horizontal section on line 4—4 of Fig. 5.

Fig. 5 is a vertical section on line 5—5 of Fig. 3.

Fig. 6 is an end elevation of the kit, the cover being shown in partly open position.

The kit shown in the drawings comprises a box 1 and cover 2 and trays 3 and 4. The box 1 has the bottom 5, front and rear walls 6 and 7 and end walls 8. The cover 2 which is secured to the box 1 by hinges 9 is provided with the front and rear walls 10 and 11, end walls 12 and top 13. The walls 6, 7, and 8 of the box 1 are shown as of uniform vertical dimension, and the walls 10, 11 and 12 of the cover 2 are likewise of uniform vertical dimension whereby to provide simplicity of appearance and construction and economy of manufacture. The box 1 and the cover 2 together form a structure of rectangular section vertically and horizontally. A partition 20 may be disposed in the box to provide a plurality of compartments therein.

The upper portions of the box walls 6, 7 and 8 may preferably be inset to form the peripheral inwardly portion 14 adjacent to and including the upper edge of the box 1 whereby the outer surface of the cover may be caused to meet flush with the outer surface of the box 1. Fastening means 15 and 16 may be provided to secure the cover 2 and box 1 in closed relation. The cover 2 is provided with a suitable handle 17 which, when the cover is opened, is adapted to rest upon the surface on which the box 1 may be disposed.

Within the box 1 and secured to the ends thereof are shown the brackets 18 which may be secured to the end walls 8 by suitable fastening means such as rivets 19. The brackets 18 have the portions 21 spaced from the end walls 8 to which links may be secured, and have also the tray supporting surfaces 22 which are preferably lower than the upper edge, or top, of the box 1 in order that the kit may be as compact as possible when closed. The trays 3 and 4 are supported on the surfaces 22 when the kit is in closed position. It will be noted that the brackets 18 contact throughout their full length directly with the respective end walls 8. In this manner is provided a more solid and rigid construction. Furthermore, with such improved brackets there is much less likelihood of the end walls becoming warped or mis-

shapen, particularly when the trays 3 and 4 are filled with heavy material.

The first or lowermost tray 3 which, when the kit is closed, rests upon the tray supporting surfaces 22 is shown as being of nearly the same length and width as the corresponding internal dimensions of the box 1 at its upper reduced portion. The tray 3 is shown as provided with partitions 23, 24 and 25 to provide compartments of desired size for the articles to be carried, for example, fishing tackle.

To the rivets A and B at each end of the tray 3 are pivotally secured the links 26 and 27 which said links are also pivotally secured respectively to the rivets D and C on the bracket portions 21. Referring to the structure at one end of the kit, the rivets A, B, C and D which define the axes of pivotal connection of the links 26 and 27, form the apices of a parallelogram ABCD whereby the links 26 and 27, as regards their pivotal connections, remain in parallel relation to permit the desired operation of the tray 3. The link 27 nearer the rear side of the box 1 is shown as being concavely curved toward the rear of the box 1 whereby said tray 3 when in outwardly extending position is disposed in a relatively low vertical plane adjacent the top rear edge of the box. It will be obvious that the desired curvature of each link 27 may be obtained by curving the link as a whole as shown in the drawings, or by curving or suitably shaping merely the rear side 28 of each link 27.

To the rivets 29 at the end of the tray 3 are pivotally secured the extensible compound links 30, each link 30 being pivotally secured at its opposite end to a rivet 31 secured to an end wall of the cover 2. Extensible links are employed between the tray 3 and the cover 2 since the distance between the pivotal connections 29 and 31 varies during the operation of opening or closing the kit. Each compound link 30 is shown as comprising link elements 32 and 33 pivotally secured together by the third link element 34. While various forms of extensible links, such as slotted links, may be employed, I prefer the compound link described because of its smooth and non-jerky operation.

The second or upper tray 4 is shown as being of substantially the same length and width as the lower tray 3. The front wall 35 of the tray 4 is shown as inclined rearwardly to permit movement of the cover past the tray in opening or closing the kit, which function will be clearly understood from Figs. 5 and 6. The tray 4 may be provided with partitions 36 to provide compartments of desired size and shape.

Links 37 and 38 are shown pivotally secured at their ends to the rivets B and 29, and 30 and 40 of the trays 3 and 4, respectively, whereby the upper tray 4 may be

readily moved independently of the tray 3. The links 38 and 37 are parallel and of equal length. Stops 41 are provided whereby when the upper tray 4 is moved into extended position said tray may be caused to take a predetermined position with respect to the lower tray 3 so that the upper tray 4 need not extend rearwardly and further than desired and so that full and complete access may be had to the lower tray 3. If desired, of course, the upper tray 4 may be arranged to be moved into outwardly extended position simultaneously with the lower tray 3. This may be accomplished by providing a single rigid link between the pivotal connections C, B and 39. The extensible links 30 might then be connected either to the lower tray 3 as shown or to the upper tray 4, and the stops 41 placed in any desired position or omitted.

Upon opening the cover 2, the compound links 30 cooperate with the rivets 29 disposed at each end of the tray 3 as indicated in Fig. 6, to pull the lower tray into the outwardly extending position shown in Fig. 2, where the lower tray 3 is disposed in outwardly extended position over the rear wall of the box 1, and the second or upper tray 4 is still superposed on the lower tray 3 as when the kit was closed. Thus where it is desired to have access to the upper tray 4 it is merely necessary to open the cover 2. When, however, it is desired to have access to the lower tray 3, the upper tray 4 may be independently moved manually to the position shown in Fig. 1 wherein, due to the position of the stops 41, the upper tray 4 is displaced sufficiently far in a vertical direction from the lower tray 3. The use of the stops 41 moreover permits the use of relatively short links 37 and 38 to move the upper tray 4 sufficiently to make the lower tray 3 readily accessible, thus rendering the kit more compact and decreasing the distance rearwardly which the upper tray 4 extends when in outwardly extending position.

When the lower tray 3 is in outwardly extending position, it and the upper tray 4 are rigidly supported from the surface upon which the kit is disposed through the handle 17, cover 2 and links 30, whereby any tendency of the kit to be overbalanced or tipped over is substantially minimized or eliminated. The links 30 thus act as an operative connection between the tray 3 and the cover 2 to provide a positive support for the tray from the surface supporting the kit. If the compound links 30 were connected to the upper tray 4 as hereinabove suggested, the said operative connection would, of course, be through the upper tray 4.

To close the kit from the position shown in Fig. 1, the upper tray 4 may first be disposed manually upon the lower tray 3 or not, as desired. If the upper tray 4 is not manually superposed upon the lower tray 3,

the cover 2 when raised and moved to closed position cooperates with the upper tray to move it into position on the lower tray 3, and then by means of the compound links 30 moves both trays into position within the kit as indicated in Figs. 5 and 6.

While I have shown and described a sheet metal kit, it will be obvious that my invention may be likewise applied to kits made of fibre, wood, or other material.

It will thus be seen that I have provided a kit of the cantilever type of simple and neat appearance and of economical construction.

It will further be noted that I have provided an improved sheet metal cantilever kit embodying advantageous features of construction whereby the box and cover of the kit may each be of uniform vertical dimension and hence which kit, when open with the trays in outwardly extending position, may have a relatively low center of gravity.

It will further be seen that I have provided a cantilever kit embodying linkage of improved characteristics.

Furthermore, it is to be understood that the particular forms of apparatus shown and described, and the particular procedure set forth, are presented for purposes of explanation and illustration and that various modifications of said apparatus and procedure can be made without departing from my invention as defined in the appended claims.

What I claim is:

1. A kit comprising, in combination, a box and a cover, a tray arranged to be carried within said kit, means carried by the box to support said tray when the kit is in closed position, parallel links secured to said box and to the ends of said tray, the rearward links being curved to permit the tray, when the kit is open, to rest over the rear wall of the box relatively closely to the top of the box to obtain a relatively low center of gravity for the structure as a whole, and extensible links secured to the rearward portion of the tray and to the cover whereby the cover may be opened substantially 90 degrees without moving said tray to make the contents of the tray readily accessible, said extensible link connections serving furthermore to provide supports for said tray when the cover is in full open position to obviate danger of rearward tipping of the tray.

2. In a horizontally divided kit including hinged box and cover portions and a tray capable of being extended over a side wall of said box portion, a pair of offset brackets secured to the inner faces of the end walls of said box portions for positively and normally supporting said tray in spaced relation with respect to the sides and bottom of said box portion, links pivoted to said brackets and tray, certain of which engage a wall of said box portion to positively support said tray in extended position, and extensible links piv-

oted to said tray and cover portion, said links being so arranged that opening the cover part way will not disturb said tray to render the contents of said tray readily accessible, but opening the cover completely will move the tray well over the rear wall of said box portion to extended position, said links when said cover is completely opened being extended to positively support said tray on said cover portion.

3. A horizontally divided kit comprising, in combination, hinged box and cover portions, a tray normally supported in spaced relation with respect to the bottom and sides of said box portion and being extendable over the rear wall of said box portion by the opening movement of said cover, a pair of parallel links pivotally secured to said box and to each end of said tray, the rearward links of each pair being arranged when said kit is open to permit the tray to rest well over said rear wall relatively closely to the edge thereof to obtain a relatively low center of gravity for the structure as a whole, and extensible links pivotally secured to the cover and to the ends of said tray whereby said cover may be opened substantially 90 degrees without moving said tray to make the contents of said tray readily accessible, said extensible links serving furthermore to provide additional supports for said tray when said cover is in full open position, thereby obviating danger of rearward tipping of said tray.

In testimony whereof I affix my signature.
35 HARRY P. SHRIVER.
